ATTORNEY

UNITED STATES PATENT OFFICE.

JOHN JOSEPH GHEGAN, OF EAST ORANGE, NEW JERSEY.

AUXILIARY DEVICE FOR TELEGRAPH KEYS.

Application filed July 10, 1919. Serial No. 309,844.

To all whom it may concern:

Be it known that I, JOHN JOSEPH GHEGAN, a citizen of the United States, residing at East Orange, Essex County, New Jersey, 5 have made certain new and useful Improvements in Auxiliary Devices for Telegraph Keys, of which the following is a specification.

This invention relates to an auxiliary device for electrically connecting a Morse telegraph key, used for manually transmitting code signals, like the Morse alphabet, and a second semi-automatic transmitting device the use of which affords increased speed in 15 transmitting with greatly decreased physical fatigue. This latter transmitter is called an "autodot."

The telegraph corporation employs thousands of Morse keys, each securely fastened 20 to its desk or table in close proximity to other instruments used in sending and receiving messages. There are two or more different patterns of these Morse keys; the most popular and most widely employed is 25 the legless key; this key has a cast brass base and lugs, which form bearings for the trunnion bearings of the arbor bearing the key lever. In addition the base carries an insulated vertically projecting screw post to receive one terminal of the divided circuit, 30 and a second similar terminal post to which the circuit closing switch is attached. Both of these projections are fixed in position in close proximity to the two lugs, respectively. 35 The insulated post is permanently, electrically connected to the down contact of the key by a metal strap, horizontal and parallel with the base. The manually operated circuit closing switch when in closed circuit 40 position slips in between strap and base electrically connecting them to cut out the circuit breaking points. All this is old and well known.

When an operator comes on duty he brings 45 with him his own "autodot" and connects it in parallel with the Morse key. This has been done heretofore by putting a wedge, having two contact surfaces, insulated from each other and forming the two terminals 50 of his autodot between the strap and the base of the Morse key; the wedge laid flat, parallel with the table-top and key base; the key switch when opened transferred the transmitting function to the autodot. The great 55 trouble with this is, and always has been, that the wedge became easily displaced and

the object of this improvement is to provide an auxiliary device for a Morse key applicable to use with keys already in use and owned by the telegraph corporation, such 60 device being cheap, immediately applicable to any key and effective to retain its position during use.

Such an auxiliary device is provided by this invention and consists of a brass strip 65 of sheet metal located vertically, having flanges on its opposite edges, and a terminal, circular in interior outline, adapting it to take its seat on the insulated projection or screw post and hold the device in vertical 70 position, parallel to a lug, as described, and in such close proximity to said lug that a wedge having two parallel, insulated flat contacts, when inserted in the space between the auxiliary contact device and lug would 75 make electrical and mechanical contact with both, while the flanges on the contact device would hold the wedge against lateral displacement. This wedge is connected, preferably by a flexible cord, to the terminals 80 of the autodot. There is a sheet of insulating material on the bottom of the auxiliary contact device suitably held in position on said contact. A set screw is used to hold the contact device on the insulated binding post. 85 One contact surface of the wedge is in electrical contact with the device and through the device with the insulated binding post, the other contact surface of the wedge is in 90 electrical contact with the lug forming the 95 uninsulated terminal of the key. The key and the autodot are thus connected in parallel; when the key switch is opened the key branch is open and the autodot is in full control.

The accompanying drawings illustrate the invention.

Fig. 1 is a side elevation of a Morse key to which the contact device is applied, with a wedge and a flexible cord connecting it 100 with the terminals of an autodot; Fig. 2 is a side elevation of the contact device; Fig. 3 is a front elevation of said device, and Fig. 4 is a top view of said device, showing the insulating material on the bottom thereof. 105

A Morse telegraph transmitting key *k* of the legless type has an insulated binding post *p*. Post *p* is connected by a metal strap 11 with the down contact 10 of the key; the circuit closer 12 connects, electrically, this 110 down contact 10 with the key base *b*. The flexible cord *c* is connected with the terminals 13

and 14 of an automatic transmitter *t*; that is the autodot *t*. The wedge *w* has two contact surfaces 15 and 16 separated by a layer of insulation 17; the contact device *d* is made from a strip of sheet metal, like sheet brass, its opposite vertical edges have flanges *f* to prevent lateral displacement of the wedge *w*; the lower end of the device *d* carries a sheet of insulating material *i* and is bent at right angles as shown in Fig. 2 to make an extended contact surface and tend to retain it in position when the opening *o* is placed over the projection *p*, and there is a set screw *s* adapted to hold it in position on post *p*. Instead of bending the sheet brass I consider it an equivalent construction to employ a section of brass pipe to which the vertical portion of the device *d* is firmly attached, this latter construction gives greater mechanical stability and in some respects is to be preferred. When the contact device is in position wedge *w* is forced in between the resilient, free contact surface of device *d* and the adjacent lug *m* integral with the key base *b*; the circuit then passes from one divided terminal of the circuit through the insulated post *p*, through contact device *d*, contact 15 of wedge *w* to terminal post 13 of the autodot, through said autodot *t*, through terminal 14 of autodot *t*, to contact 16 of the wedge and to the lug *m*, which forms the uninsulated terminal of key *k*. Key switch 12 is opened to place the transmitter *t*, the autodot, in circuit. I consider it a strong feature of merit that the wedge *w* is out of the way on the table and that the contact device retains the wedge in position unless special effort be made to displace it. The operator on changing his position from one desk to another, or on leaving his term of duty, can withdraw the wedge *w* and the contact device *d* and carry both contact device and autodot away with him. What I claim is:

1. An auxiliary connecting device for a Morse key, embodying a holding plate provided at its lateral edges with upstanding flanges, means associated with the holding plate for mounting the same upon the insulated binding post of a Morse key, with the plate intermediate the binding post and one of the fixed grounded lugs of the base, said plate being inclined in a direction away from the lug, in combination with a wedge embodying two contacts insulated from one another and forming the sides of the wedge, and adapted to constitute the terminals of wire leads, said wedge being adapted to be

thrust downwardly between the plate and the lug and into wedging engagement with both parts, and being held against tilting by the flanges of said plate. 60

2. An auxiliary connecting device for a Morse key, embodying an upwardly inclined holding plate detachably supported on the insulated binding post of the Morse key, with the plate positioned intermediate the binding post and one of the lugs of the base of said key, in combination with a wedge adapted to be forced downwardly between the plate and the lug and thereby wedged in engagement with said parts, said wedge embodying electrical contacts adapted to engage with the plate and lug when the wedge is in engagement therewith, and wires leading from said contacts. 65 70 75

3. An auxiliary connecting device for a Morse key, embodying a holding plate, means for mounting the holding plate on the insulated binding post of a Morse key, with the plate positioned between the post and one of the lugs of the base, an autodot, a wedge member embodying a pair of converging metallic contacts insulated from one another, and wires connecting said metallic contacts with the autodot, whereby the wedge member is adapted to be forced into the space between the holding plate and the lug and to come into wedging engagement with said parts for the purpose of operatively associating the autodot with the Morse key. 80 85 90 95

4. An auxiliary connecting device for a Morse key, embodying a holding plate adapted to be resiliently supported in upstanding relation on the insulated binding post of a Morse key to partake of a position between the binding post and one of the base lugs of such key, whereby a connector for an autodot may be wedged between the holding plate and the lug. 100 105

5. An auxiliary connecting device for a Morse key, embodying a holding plate adapted to be resiliently supported in upstanding relation on the insulated binding post of a Morse key to partake of a position between the binding post and one of the base lugs of such key, in combination with a wedge member embodying two diverging spring contacts insulated from one another, which wedge member is adapted to be wedged between the holding plate and the lug, and flanges formed at the lateral edges of the holding plate and adapted to grip the lateral edges of the wedge member for precluding tilting of the wedge. 110 115

JOHN JOSEPH GHEGAN.
